CLAIM

We claim the ornamental design for a portable AED (automated external defibrillator), as shown and described.

DESCRIPTION

FIG. 1 is a front perspective view of portable AED (automated external defibrillator) showing our new design; FIG. 2 is a front view thereof; FIG. 3 is a rear view thereof; FIG. 4 is a right-side view thereof; FIG. 5 is a left-side view thereof; FIG. 6 is a top plan view thereof; FIG. 7 is a bottom plan view thereof; FIG. 8 is a rear perspective view thereof; and, FIG. 9 is another front view showing the design in use. The dash-dot-dash lines represent the bounds of the claim, while all other broken lines are directed to environment and are for illustrative purposes only; the broken lines form no part of the claimed design.
